[57] CLAIM

The ornamental design for a urinal, as shown and described.

DESCRIPTION

FIG. 1 is a right, top, front perspective view of a urinal embodying my new design;

FIG. 2 is a front elevational view thereof;

FIG. 3 is a left side elevational view thereof;

FIG. 4 is a right side elevational view thereof,

FIG. 5 is a top plan view thereof;

FIG. 6 is a bottom plan view thereof;

FIG. 7 is a cross-sectional view thereof taken along line 7—7 of FIG. 2;

FIG. 8 is a cross-sectional view thereof taken along line 8—8 of FIG. 7; and,

FIG. 9 is a cross-sectional view thereof taken along line 9—9 of FIG. 2.

The broken line representation of a mounting environment in FIG. 1 is for the purpose of illustration only, and forms no part of the claimed design.
